FLAME GUN

Fred W. Funke, Oakland, Calif.

Application August 26, 1949, Serial No. 112,494

3 Claims. (Cl. 158—28)

1

This invention relates to a flame gun or flame thrower and has for one of its objects the provision of a flame gun for use in burning operations, such, for example, as are carried on by the Forestry Service, and which flame gun is adapted to operate at high efficiency over a far wider range of fuel pressure than heretofore has been possible.

The general design of flame guns of the type herein disclosed is the same in that they have a nozzle from which the fuel is ejected under pressure, and around this nozzle is a frusto-conical mouth element with its small diameter end secured to the nozzle concentric with the axis of the discharge aperture of the nozzle while the larger diameter end is open and spaced outwardly of said nozzle and coaxial with said axis. A wick pot is carried adjacent the open end of said element at its lower side and its open upper end opens upwardly into the element at its upper open end. This pot contains a wicking material of any suitable kind, such as asbestos and also a supply of fuel oil. The flame from the wick is to keep the fuel from the discharge nozzle ignited.

In the field where these flame guns are used, the operator carries a portable pressure tank for the fuel, which is ordinarily diesel or stove oil, although it can be practically any of the fuel oils other than gasoline. The tank carries a manually actuatable air pump for supplying air pressure.

The ultimate desired result is to deposit as much unburned fuel oil as possible on the material to be burned, and it must be kept ignited while being so deposited. For this reason only sufficient air should be in the fuel at the time it passes the wick pot to maintain the ejected stream ignited. The ejected fuel should have a velocity of at least substantially 48.5 feet per second at the discharge nozzle.

The principal objection to previous flame guns of the present type has been that they require a tank pressure of at least 60 lbs. per square inch to provide sufficient aeration for ignition and control of the stream. This requires frequent stoppages by the operator in order to keep up the air pressure.

One of the objects of the present invention is the provision of a nozzle design in a flame gun that will produce sufficient aeration of fuel for ignition at 16 lbs. per square inch tank pressure and maintain the same control and aeration from 16 lbs. up to 100 lbs. pressure or more without adjustment of the nozzle in any way.

2

This is quite important when it is realized that, for economy, the best pressure is from about 20 to 40 lbs. per square inch.

Heretofore, most efforts toward producing aeration have been directed toward producing a spiral passageway in the nozzle to swirl the ejected fluid, but such expedients will not operate at a pressure below 60 lbs. per square inch.

As already noted, the problem is not merely one of aeration, but of only sufficient aeration to support sufficient ignition to carry a flame to the fuel that falls onto the material to be burned, and the fuel stream should not break out of control, so as to vaporize the fuel with a consequent reduction in velocity. The fuel should carry from substantially 10 to 20 feet at pressures of from about 16 to 80 lbs. per square inch with a nozzle of the size and character hereinafter described, which is a standard size for a portable flame thrower of the type illustrated.

In the drawings,

Fig. 1 is a reduced side elevational view of the flame gun with the pressure tank diagrammatically illustrated.

Fig. 2 is an enlarged part sectional and part elevational view of the gun of Fig. 1 with the central portion of the barrel broken out.

Fig. 3 is an enlarged sectional view of the nozzle which is proportionally correct, with the frusto-conical mouth element broken away at its outer end.

Fig. 4 is a diagrammatic greatly enlarged view showing the proportional relationship between the vital parts of the nozzle.

In detail, the entire assembly comprises a flame gun 1 having a handle 2 with a manually actuatable valve control element 3 adjacent thereto. A flexible pressure hose 4 for fuel connects the handle end of the gun and a pressure tank 5 that is equipped with a manually actuatable air pump 6 for creating the desired pressure in said tank.

The main body of the flame gun is an elongated barrel 7 having the handle 2 at one end thereof and the discharge nozzle, generally designated 8, at the opposite end.

The nozzle 8 comprises an elongated cylindrical member 10 that is formed with a bore 11 therein in one end of which the outer end of barrel 7 is threaded.

The diameter of bore 11 is substantially the same diameter as that of the bore in the barrel 7 except at its end that is remote from the barrel where said diameter is reduced as at 12.

A valve rod 13 extends longitudinally through

the barrel, being connected at one end with the control element 3 adjacent the handle 2, while the opposite end is tapered to a point to seat adjacent the edges of bore 12 at the inner end of the latter. Element 3 is pivoted to the handle at 14 above its connection with rod 13, and said element extends below the point of connection between said valve rod and said element 3 to provide a trigger that is retractable by the trigger finger of a hand grasping handle 2, the latter being in the form of a pistol grip.

A collar 17 having a plurality of apertures 18 therein is centrally secured on rod 13 and is held against movement toward said pointed end by a keeper 19 on said rod.

The axially outwardly directed end of barrel 7 where it is within the body 10 of the nozzle, forms an axially directed shoulder 20 facing the collar 17. A cylindrical sleeve 21 abuts the said shoulder 20, said sleeve being centrally apertured for slidably passing the rod 13, and a plurality of passageways 23 extend through said sleeve to pass fuel into the bore 11. An expansion spring 24 around rod 13 and in bore 11 reacts between sleeve 21 and collar 17 to yieldably urge the pointed end of the valve rod tightly against the edges of the restricted diameter bore 12 in member 10.

Externally secured to member 10 at its outer end is a frustro-conical mouth element 29, the smaller diameter end of which is formed with a radially inwardly directed flange 30 that is adapted to engage an axially outwardly directed shoulder 31 formed on the outer end of the member 10. The outside of the outer end of member 10 is of reduced diameter and threaded, thus providing said shoulder 31.

Within the inner reduced diameter end of said mouth element 29 is a nozzle cap 35 that is threaded onto the outer end of said member 10. A sealing washer 36 of any suitable type may be positioned between the cap and the flange 30 so as to provide a tight seal between the cap and the element 29.

The cap 35 has an outer end wall 38 that is centrally formed with a discharge aperture 39 coaxial with bore 12.

The wall 38 is spaced from the outer end of member 10 and as the inner diameter of said cap is substantially greater than the diameter of bore 12, the space between said wall 38 and member 10 provides an enlarged chamber 40 that may be called a "turbulence chamber."

The mouth element is open at its larger diameter end which is spaced a substantial distance from the discharge aperture 39, and carried by the lower side of said element adjacent its larger diameter end is a wick pot 42 the open upper end of which opens into the element 29 flush with the inner lower side of the latter. This wick pot contains fuel oil and any suitable wicking 45, such as asbestos, so as to produce a continuous flame when ignited.

Fig. 4, the actual dimensions that are critical are given with respect to a standard sized portable flame gun as generally used with a portable pressure tank. The figures are for inches and are as follows:

$A = 0.055$ = dia. of discharge aperture 39.

$B = 0.375$ to 1.0 = diameter of turbulence chamber 40.

$C = 0.03125$ = length of discharge aperture 39.

$D = 0.5$ to 0.625 = length of turbulence chamber 40.

$E = 0.09375$ = maximum dia. of inlet aperture 12.

$F = 0.09375$ = minimum length of inlet aperture 12. 75

Insofar as the diameter A of the discharge aperture 39 is concerned, this can be varied $0.010''$ either way without materially affecting the result.

5 The dimension B, which is the diameter of the turbulence chamber 40, must not be less than $.375''$ or $\frac{3}{8}$ of an inch, but it may be from $.375$ to 1 inch without materially changing the result. As the diameter is reduced below $0.5''$ the ignition pressure increases.

The length D of the turbulence chamber, which is not less than substantially $.5$ or $\frac{1}{2}$ inch, permits the firing or ignition of the fuel at 16 lbs. pressure at the orifice or aperture 39, and which pressure will produce a velocity of 48.5 feet per second. If this length is reduced, the pressure at which the firing takes place is increased. For example, should the gap or length be reduced to $\frac{1}{8}$ inch, it would require a minimum of 60 lbs. pressure (94.5 feet per second velocity) to produce sufficient aeration for ignition. If the length were increased a distance beyond $\frac{5}{8}$ inch ($.625''$) aeration drops off rapidly and increased pressure is required the same as when the length is reduced.

20 The diameter E of the inlet aperture 12, is $.375''$ or $.09375''$ and is proportionally the maximum diameter for dimensions A and D. Even the slight increase of $0.010''$ in diameter of E shows decided loss in aeration of the stream projected through discharge aperture 39. The minimum diameter E should, of course, not be less than the diameter A and is preferably substantially $.09375''$.

25 The length F of the bore 12 is not critical except that it should not be less than $.09375''$ or $\frac{3}{32}$ ''.

30 The dimensions A, C, D and E are proportionate within relatively narrow limits. The combination is in balance hydraulically to produce aeration of the fuel stream sufficient for ignition of the fuel at a pressure as low as 16 lbs. (48.5 feet per second).

35 The ultimate purpose of the combination is to produce sufficient aeration of fuel for ignition at 16 lb. tank pressure and to maintain the same control and aeration as the pressure is increased to 100 lbs. or more. If the combination is dimensionally unbalanced (hydraulic unbalance) it would possibly work satisfactorily at one pressure point, but at no other point within the desired range. By a slight change in dimensions A, C, D or E firing and control may be obtained at 16 lbs. tank pressure, but above or below such pressure the stream would break out of control and the device would be useless. Likewise, a combination may be produced for properly firing at say 50 lbs. tank pressure, but the stream would not ignite below that pressure, although it may operate quite well up to 150 lbs. pressure.

40 With the present invention the stream will properly fire at the lowest possible pressure point (for diesel oil) and will maintain that control and stream characteristic at any point in the range as the pressure is increased to 100 lbs. tank pressure and more.

The proportions and shapes indicated in the drawings are substantially correct as shown.

I claim:

1. A flame thrower including a barrel having an inner end and an outer end with a discharge nozzle at the outer end and means for delivering fuel oil to said inner end under pressure for passage through said barrel to said nozzle, said nozzle including a through bore one end of which

defines the outlet aperture and the other end of which defines the inlet aperture, the portion of the bore between said inlet aperture and said outlet aperture being enlarged, the length of said outlet aperture axially thereof being substantially half its diameter and the diameter of said inlet aperture being at least three times the length of said outlet aperture and the diameter of said enlarged portion being at least about seven times greater than the diameter of said outlet aperture with the spacing between said outlet aperture and said inlet aperture being at least substantially ten times greater than the diameter of said outlet, the diameter of said outlet aperture being substantially from .04" to .06".

2. In a flame thrower including a discharge end having a generally frusto-conical mouth element and means for providing an ignition flame at its larger diameter open end, a nozzle secured to the smaller diameter end of said element having a discharge aperture coaxial with said element and directed toward said larger diameter end, said nozzle having a through bore, one end of which defines said discharge aperture and the other end of which defines the edges of an inlet aperture, the portion of said bore between said inlet aperture and said outlet aperture being enlarged, the length of said outlet aperture axially thereof being substantially .03125" and the diameter of said outlet aperture being substantially .055", the diameter of said inlet aperture being from .055" to .09375" and not great than the latter, the diameter of said enlarged portion being from .375" to 1" and the length of said enlarged portion axially thereof being from .5" to .625" and the length of said inlet aperture being no less than .09375".

3. In a flame thrower including a discharge end having means for producing an ignition flame for igniting oil discharged through said discharge end, a nozzle for producing aeration of oil discharged through said discharge end at comparatively low pressure, said nozzle having a through bore one end of which defines the outlet aperture and the other end of which defines the inlet aperture, the portion of the bore between said inlet aperture and said outlet aperture being enlarged, the diameter of said inlet aperture being substantially greater than the diameter of said outlet aperture but less than twice the latter and the length of said inlet aperture axially thereof being at least equal to its diameter, the length of said enlarged portion being at least equal to five times the diameter of said inlet aperture and the length of said outlet aperture being less than its diameter, the diameter of said outlet aperture being substantially from .04" to .06".
